UNITED STATES PATENT OFFICE

2,225,722

CONNECTOR OR RADIATOR CABINET

Benjamin Spieth, Racine, Wis., assignor to
Modine Manufacturing Company, Racine, Wis.,
a corporation of Wisconsin

Application May 31, 1938, Serial No. 210,987

1 Claim. (Cl. 312—189)

This invention relates to cabinets, and particularly to cabinets for covering or enclosing convectors, radiators, or similar heat exchange devices, and wherein removable front panels are provided to facilitate cleaning of the convectors or radiators.

Heretofore, in convector or radiator cabinets incorporating removable front panels, it has been the practice to slide the panel behind a retainer strip, or the like, and then to drop the panel down into a recess or the like behind a cleat or similar structure, usually resulting in scratching and otherwise damaging or marring the finish, and producing a front panel of unsightly appearance.

Front panels have also been secured in position by means of screws or bolts, necessitating the use of a tool such, for example, as a screw-driver, wrench, or the like, and which of course, interferes with the quick and convenient removal of the front panel for cleaning purposes.

One object, therefore, of the present invention is to provide a novel construction and arrangement whereby the front panel may be placed in operative cabinet-closing position and removed therefrom without damage to the finish or appearance of the panel, and without the use of any tools whatsoever, the operative positioning and removal of the panel being readily accomplished by a maid, housewife, or others frequently unfamiliar with the use of tools, and without the assistance of a mechanic.

Another object of the invention is to provide a novel construction whereby the removable panel may be set into position and removed therefrom without the necessity of dragging the panel across finished floors or carpeting, and wherein the presence of thick rugs or carpets will not interfere with the assembly of the front panel and cabinet, and the removal of the panel.

A further object of the invention is to provide a construction whereby the front panel may be conveniently and readily placed in operative position, and as conveniently and readily removed therefrom without damage to the finish of polished floors or adjacent floor coverings.

A still further object of the invention is to improve devices of the character described in sundry details hereinafter referred to and particularly pointed out in the appended claim.

One embodiment of the present invention is shown for illustrative purposes in the accompanying drawing, in which:

Fig. 1 is a front elevational view of a convector

or radiator cabinet embodying features of the present invention;

Fig. 2 is an enlarged end elevational view of the structure illustrated in Fig. 1, and shown as viewed from the right-hand side thereof;

Fig. 3 is an end elevational view of the structure illustrated in Fig. 1, showing the front panel in changed position, and illustrating the manner of placing the panel in cabinet-closing position or removing the panel therefrom; and

Fig. 4 is a further enlarged, fragmentary, sectional plan view of a portion of the structure illustrated in Fig. 2, and taken substantially as indicated by the line 4—4 thereof.

The present invention is particularly adaptable and desirable for use in homes, hospitals, offices, etc., where periodic and, at times, frequent removal of accumulated dust and dirt from within the cabinet is of utmost importance.

As illustrated in the accompanying drawing, the present invention comprises a body member formed, preferably, of sheet metal or the like, indicated, as a whole, by the numeral 6, and having end portions 7 and 8, and a top or upper portion 9.

The body member 6 and portions 7, 8 and 9 thereof adjacent their front edges are provided with a reduced portion 11 adapted to be received within the side and top portions of a removable front panel, indicated, as a whole, by the numeral 12, the front panel being provided adjacent its opposite ends and lower side portion with recesses or notches 13 adapted to receive pivot or step pins 14 mounted on the reduced portion 11 at the ends of the body member 6. The front panel 12 is also provided, adjacent its upper side or edge, with an inwardly or downwardly projecting wall 15 of relatively narrow transverse dimension having a lip 16 formed thereon adjacent its lower edge adapted to be positioned beneath a stop 17 formed on the upper side portion 9 of the member 6 and extending inwardly therefrom, as illustrated in Fig. 2, for preventing accidental displacement in an upwardly direction of the front panel 12 with reference to the body member 6.

For securing the front panel 12 to the body member, a pair of latches, each indicated, as a whole, by the numeral 18 are shown, in the present instance, as pivotally mounted at 19 on the respective end portions 7 and 8 of the body member 6, and are provided adjacent their forward or outwardly extending end portions with a recess 21 forming a hook-like portion adapted to engage

retaining pins 22 extending inwardly from the end portions of the front panel 12, as clearly illustrated in Figs. 2 and 4, for securing the panel against the front or open side portion of the body member 6 when in closed position, as illustrated in Figs. 2 and 4.

For conveniently and readily manipulating the latch 18 to disengage the hook-like portion from the retaining pin 22, and to permit removal of the front panel 12, a finger or latch pin 23 is secured to the latch 18 and adapted to extend outwardly therefrom through an elongated aperture 24 formed in the respective end portions of the body member 6, as clearly illustrated in Figs. 2, 3, and 4, thereby providing suitable means for releasing the front panel 12 for removal from the body member 6 to facilitate cleaning of the convactor or radiator within the cabinet.

It will be observed from the foregoing description that to position the front panel 12 on the body member 6, it is necessary only to place the front panel in a position so that the recesses 13 will engage the pivot or step pins 14, as illustrated in Fig. 3, and by swinging the upper end of the panel 12 inwardly toward the body member and raising the latch to engage the retaining pin 22, the panel member will be secured to the front or open side portion of the body member, as clearly illustrated in Fig. 2 with the lip 16 in position beneath the stop 17 to prevent accidental displacement of the front panel in an upwardly direction, and by reason of the reduced portions 11 of the body member 6 being positioned within the end walls of the front panel 12, the panel is secured against accidental displacement in an endwise direction with respect to the body member. Also, that to remove the panel from the body member, it is necessary only to lift the finger or latch pins 23 to disengage the latch 18 from the retaining pins 22, and by swinging the upper end of the front panel outwardly, the panel may be lifted out of engagement with the pivot or step pins 14, thereby permitting quick removal of the front panel and convenient access to the convactor or

radiator within the body member for cleaning or other purposes.

It will be observed also that the present invention provides a novel and most convenient means for obtaining access to the interior of the cabinet without the use of tools, and by means, which may be readily manipulated by a maid, housewife or others, and without the services of a mechanician.

Obviously, the present invention is not limited to the precise construction and arrangement shown and described, as the same may be variously modified. Moreover, all the features of the invention need not be used conjointly as the same may be used to advantage in variously different combinations and sub-combinations.

What I claim as new and desire to secure by Letters Patent is:

In a convactor cabinet and in combination, a body member having an open front side portion, a removable front panel adapted to close the open front side of said member, a pair of pivot or step pins mounted in the respective lower end portions of said member adjacent the open side thereof, a downwardly extending stop on said member adjacent the upper front edge portion thereof, said panel having recesses formed in the respective end portions thereof and adapted to receive said pivot pins, a lip on the upper edge portion of said panel adjacent said stop and engageable therewith for securing said panel against vertical displacement with respect to said body member when the panel is in operative position with respect thereto, retaining pins mounted on the respective inner sides of the end portions of said panel, movable latch members pivotally mounted on the inner sides of the end portions of said body member and operatively related to said retaining pins for securing the body member and panel together, and manually actuated means extending through the end portion of the cabinet and operatively related to said latch members for disconnecting the latches from said retaining pins.

BENJAMIN SPIETH.
